UNITED STATES PATENT OFFICE.

JOSEPH POLK CHERRY, OF NASHVILLE, TENNESSEE.

DESIGN FOR A BOTTLE.

SPECIFICATION forming part of Design No. 21,500, dated April 26, 1892.

Application filed April 2, 1892. Serial No. 427,545. Term of patent 14 years.

To all whom it may concern:

Be it known that I, JOSEPH POLK CHERRY, of Nashville, in the county of Davidson and State of Tennessee, have invented a new and original Design for a Bottle, of which the following is a full, clear, and exact description.

Reference is to be had to the accompanying drawing, forming a part of this specification, in which the figure is a perspective view of a bottle embodying my new design.

The design consists in the novel configuration shown.

In general the bottle is coniform and terminates in a convex top *a*, having a projection or overhanging bead *b*. At the front of

the otherwise coniform body appears a recess, the bottom wall *c* of which is flat, relieved by a raised neck *c'*. The side or inner wall *d* of the recess rises from the bottom wall *c* in an upward and outward direction in the form of a section of a conical figure joining the conical external lines of the body near the top. 2c

I claim—

The design for a bottle, herein shown and described.

JOSEPH POLK CHERRY.
